TYPE WRITING MACHINE.
APPLICATION FILED JUNE 6, 1902.

2 SHEETS—SHEET 2.

UNITED STATES PATENT OFFICE.

WALTER J. BARRON, OF BROOKLYN, NEW YORK, AND HENRY W. MERRITT, OF SPRINGFIELD, MASSACHUSETTS, ASSIGNORS TO DENSMORE TYPEWRITER COMPANY, OF SYRACUSE, NEW YORK, A CORPORATION OF NEW YORK.

TYPE-WRITING MACHINE.

SPECIFICATION forming part of Letters Patent No. 783,669, dated February 28, 1905.

Original application filed February 6, 1902, Serial No. 92,839. Divided and this application filed June 6, 1902. Serial No. 110,481.

To all whom it may concern:

Be it known that we, WALTER J. BARRON, a resident of the borough of Brooklyn, county of Kings, city of New York, and State of New York, and HENRY W. MERRITT, a resident of Springfield, county of Hampden, and State of Massachusetts, citizens of the United States, have invented certain new and useful Improvements in Type-Writing Machines, of which the following is a specification.

This case is a division of our application filed February 6, 1902, Serial No. 92,839.

Our invention relates to type-writing machines, and more particularly to the carriage-feed mechanisms thereof.

One object of our invention is to provide simple and efficient mechanism of the character described.

A further object of our invention is to provide simple and efficient mechanism for stepping the carriage back in a direction opposite to that of its feed.

To these and other ends which will hereinafter appear our invention consists in the features of construction, arrangements of parts, and combinations of elements to be hereinafter described and claimed.

In the accompanying drawings, wherein like reference characters designate like parts in the various views, Figure 1 is a vertical sectional view of one form of type-writing machine embodying our invention, the section being taken from front to rear of the machine. Fig. 2 is a detail side view of a portion of the mechanism for back-stepping the carriage. Fig. 3 is a rear elevation of the same. Fig. 4 is an enlarged central vertical section of the feed or escapement wheel and certain of its coöperating parts, the section being taken on line $x-x$ of Fig. 5. Fig. 5 is a rear sectional view of the feed-wheel and a portion of its coöperating mechanism, certain parts being broken away to show others.

We have shown the various features of our invention applied to a Densmore type-writing machine; but it should be understood that they or one or more of them may be employed in type-writing machines of other makes.

1 designates the main frame of the machine,

2 the usual top plate, and 3 the key-levers, which are connected by links 4 in a suitable manner to actuate the type-bars 5, which are pivoted to hangers 6, secured to the top plate 2. Each of the key-levers 3 is provided with the usual figure-key 7 and with a hook 8, which bears upon a transverse universal bar 9, that has a rearwardly-extending arm at each end, which is pivoted to the frame of the machine at 10. Pivoted to the universal bar 9 at 11 is a link 12, preferably made of two parts, which may be adjustably united by screw-threaded connections 13. The upper end of this link 12 is provided with an eye 14, that engages a notched portion 15 of an arm 16, which is preferably in the form of a screw 65 that extends through a threaded hole in a depending stud 17 of the dog-rocker, whereby the said arm may be adjusted to bring the inner end thereof closer to or to move it farther from the pivotal center of the rocker 70 in order to vary or regulate the throw imparted to the rocker and the feed-dogs carried thereby. The adjustment 13 enables the link 12 to be lengthened or shortened in accordance with the adjustment of the arm 16. The feed-dogs 18 and their rocker 19 after actuation are returned to normal position by a spring 20, which is suitably connected at one end to an arm 20^x on the rocker (see Fig. 5) and at its other end to a fixed arm 21 on the machine-frame. The feed-dogs 18 and 18^x coöperate with a feed-wheel 22, which, as will be seen upon reference to Figs. 4 and 5, is secured to a sleeve 23, that surrounds and is loosely carried upon a shaft 24 and is prevented from moving longitudinally thereon in one direction by a sleeve 23^a, which is secured to the shaft 24 by a set-screw.

The shaft 24 has cone-bearings at its ends which coöperate with antifriction-balls 24^a, (see Fig. 1,) which revolve in circular raceways. One raceway is formed in a bracket 24^b, that is secured to the top plate 2 of the machine, and the other raceway is formed in a screw-threaded adjustable plug 24^c, that takes 95 into a threaded opening in the bracket-arm 24^d, which forms part of the bracket 24^b. By these means an efficient ball-bearing support

is provided for the shaft 24, and the plug 24^c may be turned by a screw-driver (a slot being provided in the plug for this purpose) to compensate for any wear that may take place in the balls or the bearings.

Screws 25, which unite the sleeve 23 to the feed-wheel 22, likewise connect a ratchet-wheel 26 to the feed-wheel to rotate therewith. The teeth of the ratchet-wheel 26 are disposed in an opposite direction from the teeth of the feed-wheel, as may be clearly seen upon reference to Fig. 5.

Mounted to one side of the feed-wheel 22 is a back-stepping ratchet-wheel 27, which is provided with a laterally-extending collar or boss 28, that surrounds the shaft 24 and is connected thereto and to a shaft 29^x, which is secured to or forms part of a feed-pinion 29, by a set-screw 30. The back-stepping ratchet-wheel 27 is provided with a laterally-projecting circular flange 31, which extends toward the feed-wheel 22 and surrounds the intermediate ratchet-wheel 26, connected thereto. The ratchet-wheel 27 has pivoted thereto within the flange 31 a pawl 32, which is normally maintained in engagement with the ratchet-wheel 26 by a spring 33. The flange 31, in addition to acting as a housing for the pawl 32 and ratchet 26, constitutes an abutment to prevent a longitudinal movement in one direction of the escapement or feed wheel 22 and the sleeve 23, to which it is connected.

Pivoted to a fixed portion of the machine is a back-stop pawl 34, the pivot of which is indicated at 35. The engaging nose 36 of this pawl is normally pressed in the direction of the feed-wheel by a spring 37, that bears at one end upon a fixed portion of the machine at 38 and at the other end upon the pawl 34 at 39. The lower end of this pawl 34 is extended at 40 to form a stop that is adapted to abut against a fixed part at 41 to limit the movement of the pawl toward the feed-wheel 22.

When the parts are in the normal position, the pawl 34 will engage the back of one of the teeth of the feed-wheel, as shown in Fig. 5, and prevent a backward movement of the feed-wheel, whereas a rotation of the feed-wheel in the direction of the arrow in Fig. 5, which corresponds to the feed movement of the carriage, will cause the pawl 34 to be deflected to one side to permit a free movement of the feed-wheel. The feed-pinion 29 is adapted to engage and coöperate with the teeth 42 of a feed-rack 43, that is carried by the carriage *a*, which carries the platen *b*.

From the foregoing description it will be understood that a feed movement of the dogs will permit the feed-wheel to rotate in the direction of the arrow in Fig. 5, and thus permit the carriage connected thereto to be moved by its usual driving-spring *c* in the direction of its feed and in an opposite direction to that indicated by the arrow on the feed-rack in Fig. 3 of the drawings. In this movement of

the parts the carriage-driving spring moves the rack 43, which turns the pinion 29, shaft 24, and ratchet-wheel 27, carrying the pawl 32. The pawl 32 turns the ratchet-wheel 26 and the feed-wheel 22, connected thereto. When, however, the carriage is moved back to the initial position, the pawl 32, which is operatively connected to the feed-pinion 29, rotates with the back-stepping wheel 27 in the reverse direction, and the engaging end of the pawl 32 will ride over the teeth of the coöperating ratchet-wheel 26, thus permitting the feed-wheel 22 to remain fixed against movement while the carriage is being restored to the initial position to begin a line of writing.

The pawl 34 is employed to provide against any accidental reverse movement of the feed-wheel during the return of the carriage. This pawl 34, as before explained, immediately engages the rear of one of the teeth of the feed-wheel and prevents a movement thereof in a direction opposite to that of the arrow in Fig. 5, thus maintaining the feed-wheel against reverse movement and in a position where it is ready to coöperate with the feed-dogs to permit a movement of the carriage in the direction of its feed.

It is sometimes desirable to step the carriage back one or more letter-space distances in a direction opposite to that of its feed for the purpose of making a correction—as, for example, when a character has been omitted in a word. For this purpose we have provided at the keyboard of the machine a special key 44 on a lever 45, that has a depending projection 46. This key-lever 45 may be pivoted at 47, and the projection 46 thereof is adapted to coöperate with a crank-pin 48, carried upon a collar 49, that is rigidly secured to a rock-shaft 50. This rock-shaft 50 has a crank-arm 51 extending therefrom, and the rear or free end of this crank-arm is pivotally connected at 52 to an upwardly-extending arm or ligament 53, which carries at its upper end a back-stepping pawl or hook 54, that is guided in its movements by a pin-and-slot construction 55 56, the pin 55 being on a fixed portion of the machine and the slot 56, which is inclined, being on the pawl. A depression of the key 44 will cause the projection 46 to descend and the shaft 50 to be rocked and the crank-arm 51 to be moved down. This downward movement of the crank-arm 51 draws down the pawl 54 and causes it to engage a tooth of the back-stepping ratchet-wheel 27 and turns the latter for a portion of a revolution. The movement thus transmitted to the back-stepping ratchet-wheel 27 will be imparted to the feed-rack and carriage to move the same in the direction of the arrow in Fig. 3. During this movement of the back-stepping wheel the pawl 32, carried thereby, will ride freely over the teeth of its coöperating ratchet-wheel 26, so that at this time no movement is transmitted in the feed-wheel.

120

125

130

single depression of the key 44 will impart a movement to the back-stepping wheel a distance which corresponds to one letter-space distance, and when the key is released the key 5 and its coöperating parts will be restored to their normal positions by a coiled spring 44^x. (See Fig. 3.)

The feed-rack 43, hereinbefore referred to, is mounted upon arms 57, that project from a 10 rock-shaft 58, to which is secured a leaf-spring 59, (see Fig. 1,) the free end of which bears against a portion of the carriage, as shown at 60, in order to maintain the feed-rack 43 normally in engagement with its co- 15 operating feed-pinion 29. The rock-shaft 58 is likewise provided with a lug 61, which is bifurcated at 62, so as to provide stops 63, that coöperate with a fixed pin 64, carried upon the carriage, in order to limit the oscillation of the rock-shaft. The rock-shaft 58 has a finger-piece or arm 65 secured to one end thereof, preferably the left-hand end, so that a depression of this finger-piece or arm 65 will rock the shaft 58, thus disengaging the 20 feed-rack 43 from its pinion 29 to permit the carriage to be freely moved in either direction.

Various changes may be made in detail construction without departing from the spirit of our invention.

30 What we claim as new, and desire to secure by Letters Patent, is—

1. In a type-writing machine, the combination of a feed-rocker, feed-dogs carried thereby, key-levers, a universal bar operated by 35 said key-levers, an intermediate two-part link between said universal bar and rocker, the said parts being adjustable one with relation to the other to lengthen or shorten the link, and a screw-arm carried by said rocker and to 40 one end of which the link is connected, whereby the screw-arm may be turned in its bearings to project one end of the screw-arm farther from or to draw it nearer to the rocker to change the relation between the rocker and link and thus regulate the throw of the former.

2. In a type-writing machine, the combination of a power-driven carriage a feed-rack carried by said carriage, a feed-pinion mounted upon the framing of the machine, an escapement-wheel loosely mounted upon the shaft of the feed-pinion, a ratchet-wheel rigidly secured to the escapement-wheel, a back-feed wheel fixed to said pinion-shaft, a pawl carried by the back-feed wheel and adapted to 50 engage the ratchet-wheel which is secured to the escapement-wheel, feed-dogs which coöperate with the escapement-wheel, and means for operating the back-feed wheel for moving the carriage in a direction opposite that of its feed.

3. In a type-writing machine, the combination of a power-driven carriage, a feed-rack carried by said carriage, a feed-pinion mounted upon the framing of the machine, an escapement-wheel loosely mounted upon the shaft of

the feed-pinion, a ratchet-wheel rigidly secured to the escapement-wheel, a back-feed ratchet-wheel fixed to said pinion-shaft, a pivoted spring-pressed pawl carried by the back-feed ratchet-wheel and adapted to engage the 70 ratchet-wheel which is secured to the escapement-wheel, feed-dogs which coöperate with the escapement-wheel, and a pawl for operating the back-feed ratchet-wheel for moving the carriage step by step in a direction opposite to that of its feed. 75

4. In a type-writing machine, the combination of a power-driven carriage, a feed-rack carried by said carriage, a feed-pinion mounted upon the framing of the machine, an escapement-wheel loosely mounted upon the shaft of the feed-pinion, a ratchet-wheel rigidly secured to the escapement-wheel, a back-feed ratchet-wheel fixed to said pinion-shaft, a pivoted spring-pressed pawl carried by the back-feed ratchet-wheel and adapted to engage the 80 ratchet-wheel which is secured to the escapement-wheel, feed-dogs, which coöperate with the escapement-wheel, a back-feed pawl for operating the back-feed ratchet-wheel and 85 which is normally out of engagement therewith, and a key at the keyboard which is operatively connected to the back-feed pawl for moving the carriage step by step in a direction opposite to that of its feed at each depression of said key. 90

5. In a type-writing machine, the combination of a power-driven carriage, a feed-rack carried by said carriage, a feed-pinion mounted upon the framing of the machine, an escapement-wheel loosely mounted upon the shaft of the feed-pinion, means for preventing a backward rotation of the escapement-wheel, a ratchet-wheel rigidly secured to the escapement-wheel, a back-feed wheel fixed to said 100 pinion-shaft, a pawl carried by the back-feed wheel and adapted to engage the ratchet-wheel which is secured to the escapement-wheel, feed-dogs which coöperate with the escapement-wheel, and means for operating the back-feed wheel for moving the carriage in a direction opposite to that of its feed. 105

6. In a type-writing machine, the combination of a carriage, a rack carried by the carriage, a feed-pinion meshing with said rack, a 110 shaft detachably connected to the feed-pinion, means for affording a disconnection of the pinion from said shaft, an escapement-wheel carried by said shaft, and ball-bearings which support the shaft. 115

7. In a type-writing machine, the combination of a carriage, a rack carried by the carriage, a feed-pinion meshing with said rack, a shaft for the feed-pinion, an escapement-wheel carried by said shaft, antifriction-balls 120 which support the shaft, bearings for said balls, one of said bearings being at an end of the shaft and another intermediate of the feed-pinion and escapement-wheel, and means for adjusting the bearings one with relation to 125 130

another to compensate for wear upon the parts.

8. In a type-writing machine, the combination of a shaft, an escapement-wheel carried by and operatively connected to said shaft, a pinion detachably connected to said shaft, roller-bearings on the shaft at one end thereof and also intermediate the escapement-wheel and pinion, coöperating rollers, roller-bearings on a fixed portion of the machine at one end of the shaft and intermediate the pinion and escapement-wheel, and 10 bearings on a fixed portion of the machine at one end of the shaft and intermediate the pinion and escapement-wheel.

9. In a type-writing machine, the combination of a shaft, an escapement-wheel carried by and operatively connected to said shaft, a back-spacing ratchet-wheel connected to the shaft, a key-actuated pawl coöperating with 15 said back-spacing ratchet-wheel, means for

guiding the pawl, a pinion detachably connected to said shaft, roller-bearings on the shaft at one end thereof and also intermediate the escapement-wheel and pinion, coöperating rollers, roller-bearings on a fixed portion of the machine at one end of the shaft and intermediate the pinion and escapement-wheel, and 20 means for adjusting one of said bearings on a fixed portion of the machine.

Signed in the borough of Manhattan, city of New York, in the county of New York and State of New York, this 2d day of June, A. D. 25 1902.
